UNITED STATES PATENT OFFICE

2,311,882

ACOUSTICAL TOY RAILROAD STATION

William R. Smith, Philadelphia, Pa., assignor to
The A. C. Gilbert Company, New Haven, Conn.,
a corporation of Maryland

Original application April 21, 1939, Serial No.
269,185, now Patent No. 2,247,418, dated July
1, 1941. Divided and this application Septem-
ber 9, 1939, Serial No. 294,109

9 Claims. (Cl. 274—15)

This invention relates to an acoustical toy railroad station or depot in which a phonograph completes a cycle of sound reproducing action, then automatically terminates its production of sound and reconditions itself for repeating the same cycle of action when such cycle is next begun. The invention further relates to particular constructions and arrangements of apparatus comprising the sound reproducing phonograph. This application is divisional from my copending application Serial No. 269,185, filed April 21, 1939, which has eventuated in Patent No. 2,247,418, granted July 1, 1941.

One object of the invention is to conceal within the housing structure of a conventional toy railway station or depot all of the apparatus necessary for producing sound effects realistically imitative of the noises associated with the stopping and starting of a steam locomotive and of the familiar shouted announcements of an imaginary station agent regarding the destination and way stations of a toy train which pauses in front of the station during such announcements.

A further object is to provide a system of electro-mechanical agents adapted to carry through a cycle of sequential electrically controlled acoustical effects and then automatically terminate its own action.

A further object is to make use of a shallow toy station platform structure for housing a disc type of phonograph record which record consequently may be of such large diameter that the area of its surface which carries the sound track considerably exceeds the floor area of the station house or superstructure mounted on such platform.

A still further object is to provide a simplified self-repeating reproducer for "playing" a phonograph record to produce these particular sound effects, or in connection with phonographic reproduction for any purpose whatever.

The foregoing and related objects of the invention will become clear from the following description of the details of a preferred embodiment thereof, in which description reference is had to the accompanying drawings, wherein:

Fig. 1 is a plan view of a toy railway station or depot such as that more fully illustrated in my aforesaid patent, the roof being broken away to expose the sound producing apparatus contained therein and the floor partition also being broken away to expose portions of a phonograph record therebelow.

Fig. 2 is a front elevation of said apparatus and phonograph record exposed by breaking away

portions of the surrounding side walls of the station building and platform, the reproducer needle being raised from the record.

Fig. 3 is a fragmentary view of the apparatus of Fig. 2 showing the reproducer needle lowered into playing position on the record and tilted to a different position.

Fig. 4 is a fragmentary plan view of the parts positioned as in Fig. 3.

Fig. 5 is a view taken in section on the planes 5—5—5—5 in Fig. 1 looking in the direction of the arrows.

Fig. 6 is a view taken in section on the plane 6—6 in Fig. 1, looking in the direction of the arrows.

Fig. 7 is a diagrammatic view of the electro-mechanical cycle controller and its circuit connections.

Fig. 8 is a fragmentary view taken in section on the plane 8—8 in Fig. 1.

The sound producing apparatus of the present improvements is located partly within the toy station building 10 and partly within the hollow station platform 11. Upon the floor partition 12 of the combined station and platform structure and within the walls 13 of the toy station building there is mounted any suitable electric motor 14. To prevent the motor hum or vibration from being magnified by the sheet metal of the station structure, pads 15 of soft rubber or like vibration dampening material may be squeezed between the motor feet 20 and the floor partition 12 by mounting screws 16. The motor shaft 17 has worm threads 18 cut upon it.

A vertical shaft 19 has its top bearing in the flange 21 of an upstanding bracket 22 whose oppositely turned bottom flange is secured to the floor 12 by screws 24. Shaft 19 is given additional bearing where it passes through the floor partition 12 and it projects therebelow to receive the nut 26 on the threaded terminal of a lower end portion of the shaft having a reduced diameter to produce the shoulder 25. A shouldered collar 28 is carried on the reduced portion of shaft 19 and seats against the shoulder 25, the smaller diameter of which collar fits the central aperture in a disc phonograph record 29 which is centralized thereby and clamped against the top flange of the collar by a plate-like turntable 27 forced upwardly by the nut 26. Shaft 19 carries fixed thereon the worm wheel 31 which is spaced slightly above the bracket flange 21 by a thrust washer 30 and which is in mesh with and driven by the worm threads 18 of the motor shaft 17. Between its top and bottom bearings,

shaft 19 has the worm threads 32 cut thereon. The upstanding wall of bracket 22 affords bearing for one end of a horizontal cam shaft 33 whose opposite end is journaled in an upstanding bracket 34 secured to the floor partition 12 by the screw 35. A worm wheel 37 is fixed to shaft 33 and meshes with the threads 32 on the shaft 19. Worm wheel 37 is separated from bracket 22 by a thrust washer 36. Fixed to shaft 33 is the cam cylinder 38 having in axially displaced relationship a mechanical actuating hump 39, and an indented recess 43 cooperative with a spring leaf type of electric contact 44.

Contact 44 is mounted on a block 46 of electrical insulative material secured to the floor partition 12 and adapted to serve as a terminal binding post base for the convenient connection and inter-connection of certain conductors more fully identified in Fig. 7. Two binding posts provided for this purpose are numbered respectively 49 and 50. Binding post 49 is in electrical contact with, and if desired may serve to secure, leaf contact 44 to the insulative block 46. Except as connected by lead wires or to "ground," it will be understood that each of binding posts 49 and 50, is electrically insulated from the other and from all other metallic parts of the apparatus.

Situated at the right of the foregoing described apparatus in Figs. 2 and 3 are two widely spaced upstanding brackets 52 and 53, each secured to the floor partition 12 by screws 54. Spanning the space between brackets 52 and 53 and journaled therein by means of its trunnions 55 is a sound reproducer 56 which may be of generally cylindrical or disc-like shape and preferably provided with a weight offset on the left side of the axis of its trunnion 55 in the form of the projecting body 58. Reproducer 56 may constitute any of the well known forms of devices for producing by means of a contained diaphragm audible vibrations responsive to vibrations imparted to its downwardly extending needle 59 by the sound track 60 on the top surface of record 29. Needle 59 reaches the record by extending downwardly through an aperture 57 in floor partition 12. The weight of the reproducer 56 is permitted to press the needle point against the record because of the positioning of its bearings in the brackets 52 and 53 which bearings are arranged at a height normally permitting the needle to track upon the record.

The bearing for the reproducer trunnion in the front bracket 53 may comprise a vertically elongated slot 61 opening through the top edge of the bracket, while the bearing for the other trunnion in the rear bracket 52, although it may be a closed hole, will preferably permit enough play of that trunnion to allow the front trunnion to rise and fall in the slot 61 a sufficient distance to on occasion lift the needle 59 from the record and later restore it into playing contact therewith. For so lifting the front trunnion, a bell crank lever 62 is pivoted to bracket 53 at 63 so that its lower or follower end 64 may swing into and out of the path of the cam hump 39. When forced by this hump to swing counter-clockwise about pivot 63, the upper end of lever 62 will cam under the trunnion 55 and lift it sufficiently to remove the needle 59 from engagement with the record. If desired, any of the now common forms of electrical pickup heads may be substituted for the mechanical sound reproducer 56.

The operation will be described with particular reference to the electro-mechanical diagram of

Fig. 7 in which certain structural parts are designated by the same reference characters as in other figures of the drawings. The normal condition of the apparatus within the station is that shown in Figs. 5 and 7 in which the sound reproducer needle 59 is resting on the sound track of record 29, electrical contact is broken between 44 and 38 because of recess 43. The self-opening switch 70 may be temporarily closed manually or by the arrival of a train at a predetermined point along the track. The heavy single lines in Fig. 7 indicate electrical conductors as follows. Conductors 103 connect one side of a battery 99, or other source of electrical power such as a toy transformer, to one terminal of switch 70 and also with the rotating cam cylinder 38 or any part in a "ground" circuit therewith. Conductor 105 connects the other terminal of switch 70 with binding post 49 and hence with leaf contact 44. Still another conductor 106 connects binding post 49 with one terminal of an electric motor 14. Still another conductor 101 connects the other terminal of motor 14 with the battery, transformer or other source of power 99.

Through the circuits formed by these conductors connected as described, the first effect of closing switch 70 is to complete the circuit 99—103—105—106—14—101. This energizes the motor 14 which instantly, through worm 18, worm wheel 31, shaft 19, worm 32, worm wheel 37, and shaft 33, starts to rotate cam cylinder 38 counter-clockwise in Figs. 5 and 7. At the same time, the turning of said shaft 19 rotates the turn table 27 at usual turn table speed together with the disc phonograph record 29 carried thereon. Almost at the instant cylinder 38 begins to rotate, recess 43 is removed from register with the free end of leaf contact 44 so that the latter is contacted and wiped by the periphery of the cam cylinder, the latter being of good electrical conductive material. This sets up and maintains for the duration of a predetermined automatic cycle of operations (represented by one complete revolution of cam cylinder 38) the following additional electric circuit 99—103—38—44—49—106—14—101. Hence when switch 70 is manually or otherwise released and permitted to open, current continues to be supplied to motor 14 throughout said automatic cycle of operations.

Sound reproduction is thus begun and continues while needle 59 tracks toward the left from its position in Fig. 5 to its position in Fig. 3 as motor 14 continues to rotate cylinder 38 counter-clockwise. When cylinder 38 is nearing the completion of a full revolution, the cam hump 39 swings lever 62 counter-clockwise which lifts the front trunnion 55 in its bearing slot 61 tilts the axis of the trunnions and raises it from the position shown in Fig. 3 and by broken lines in Fig. 6, to a position free and clear of the sound track as shown by full lines in Fig. 6. Thereupon the reproducer head 56 is swung smartly counter-clockwise by the force of its offset weight 58 and to an extent limited by the stop 51 as shown in Fig. 2. A further small degree of rotation of the cam cylinder 38 counter-clockwise causes the hump 39 to pass the follower end 64 of lever 62 so that the latter is permitted to return to its position shown in Fig. 5 whereby the needle is lowered again into engagement with the beginning or radially outer portion of sound track 60 on the record ready to repeat its cycle of sound reproduction. When switch 70 is next

closed the automatically terminated cycle of phonograph playing will be repeated.

If the recess 43 is omitted from cylinder 38 there will be no automatic stopping of the latter and it will be rotated continuously by motor 14 whereupon the record will be played over and over automatically, thus perpetually repeating reproduction of all sound recorded thereon so long as motor 14 is operating. In this proposed modification, switch 10 may be left permanently closed or is not needed.

Departures from the particular details of apparatus and electric circuits herein disclosed and many possible substitutes therefor will occur to those skilled in the art. The appended claims are intended to cover all such substitutes and equivalents which fall fairly within the scope of their terms.

I claim:

1. A composite toy railroad depot and contained sound emitting apparatus, embodying the combination with a rotatably supported phonographic disc record, of a motor, a reproducer, a hollow toy depot platform too shallow to house said motor and reproducer but housing said record, a hollow toy depot building superimposed on said platform having a floor area too small to house said record but housing said motor and reproducer, connections extending from said motor in said toy building to said record in said toy platform constructed and arranged to transmit rotary drive from said motor to said record, and additional connections extending from said reproducer in said toy building to said record in said toy platform constructed and arranged to track on said record, by which arrangement the portions of said apparatus whose general dimensions accord with the conventional proportions of a depot building and a depot platform respectively are housed respectively by said toy building and toy platform in a manner to conceal and camouflage all of said apparatus within a composite depot building and platform of conventional toy size and appearance.

2. An acoustical toy railway depot embodying in combination, a hollow depot platform and a superimposed hollow toy depot building separated by an apertured floor-like partition, an apertured phonographic disc record, a turntable constructed and disposed to support said record for rotation in a plane parallel to and beneath said partition, a motor supported above said partition within said depot building, a vertical shaft connected to be driven by said motor and extending downward through said partition and through the aperture in said record and connected to support and rotate said turntable at its lower end, a sound reproducer supported within said depot building above said partition, and means extending downward from said reproducer past the plane of said partition in a manner to reach and track on said record for transmitting sound producing oscillation from the record to the reproducer.

3. An acoustical toy railway depot as defined in claim 2, in which the said sound reproducer includes a body portion pivotally supported within the said depot building above the said floor-like partition, and the said means comprises a pick-up needle carried by said reproducer body and extending downward from the interior of said depot building to the interior of the said depot platform through an aperture in said partition.

4. In a phonograph, in combination, a rotat-

able disc record having a sound track on one flat face thereof, a sound reproducer having a record tracking needle, and means pivotally supporting said reproducer including trunnions fixed to and projecting laterally from said reproducer together with support walls flanking said reproducer affording bearing seats on opposite sides of the latter respectively occupied by and loosely fitting said trunnions, at least one of said seats being vertically elongated to permit and guide up and down movement of at least one of said trunnions, whereby said needle may on one occasion swing crosswise of said sound track in an arc of pendulum-like travel about a pivotal axis and on another occasion track on said record in a translatory path of travel.

5. In a phonograph for playing a rotatable record having a sound track, resettable reproducer operating mechanism including the combination with a sound reproducer having a record tracking needle, of means pivotally supporting said reproducer in a manner enabling said needle to swing crosswise of said sound track in an arc of a pendulum-like travel about a pivotal axis, said supporting means including structure providing sufficient freedom for said reproducer to permit up and down movement of said reproducer and of its said pivotal axis, thereby to enable said needle to track on said record in a translatory path of travel together with means urging said needle to swing crosswise of said sound track with a force sufficiently light to be overcome by the sound producing tracking of said needle upon said record while the latter is being rotated, and mechanism operatively related to said reproducer in a manner to raise the latter and its said pivotal axis sufficiently to lift said needle out of engagement with said sound track and permit said reproducer to be swung freely by said means.

6. Phonographic apparatus particularly suited for housing and concealment by the hollow structure of a conventional toy railway depot, embodying in combination, a horizontally disposed turntable for supporting a disc record, means to support said turntable for rotation including a bearing frame bridging over the space occupied by said turntable, power mechanism including a motor for rotating said turntable supported over the latter by said frame, a reproducer constructed and arranged to track on the record and supported over said turntable by said frame, and mechanical connections motivated by said mechanism and operative to shift said reproducer and supported over said turntable by said frame.

7. Phonographic and electric current controlling apparatus particularly suited for housing and concealment by the hollow structure of a conventional toy railway depot, embodying in combination, a horizontally disposed turntable for supporting a disc record, means to support said turntable for rotation including a bearing frame constructed and arranged to bridge over the space occupied by said turntable, power mechanism including a motor for rotating said turntable supported over the latter by said frame, a reproducer constructed and arranged to track on the record and supported over said turntable by said frame, and mechanical connections motivated by said mechanism and operative to shift said reproducer and also supported over said turntable by said frame, together with an electrical controller for governing said motor connected to be mechanically op-

erated by the latter and also supported over said turntable by said frame.

8. Phonographic apparatus particularly suited for housing and concealment by the hollow structure of a conventional toy railway depot, embodying in combination, a horizontally disposed turntable, a centrally apertured disc record carried on said turntable, means to support said turntable for rotation including a bearing frame constructed and arranged to bridge over the space occupied by said turntable, power mechanism including a motor for rotating said turntable supported over said record by said frame, a drive shaft journaled in said frame and passing downward through the aperture in said record and connecting with said turntable therebelow, a reproducer constructed and arranged to track on said record and supported thereover by said frame, and mechanical connections motivated by said mechanism and operative to shift said reproducer also supported over said record by said frame.

9. An acoustical toy railway depot embodying in combination, a hollow toy depot platform and a superimposed hollow toy depot building, an apertured floor-like partition horizontally disposed between the respective interiors of said platform and building, a phonographic disc record supported to rotate within said platform interior beneath said partition, a motor supported above said partition within said building interior, means extending through said partition for transmitting movement from said motor to said record, a sound reproducer supported within said building interior above said partition and means extending from said reproducer past said partition, in a manner to reach and track on said record for transmitting sound producing oscillations from the latter to said reproducer.
